US00D739232S

(12) **United States Design Patent**
Sanfilippo et al.

(10) **Patent No.:** **US D739,232 S**
(45) **Date of Patent:** **** Sep. 22, 2015**

(54) **FILM USED TO MAKE PACKAGES**

(71) Applicant: **CLEAR LAM PACKAGING, INC.**,
Elk Grove Village, IL (US)

(72) Inventors: **James J. Sanfilippo**, Barrington Hills,
IL (US); **John E. Sanfilippo**, Barrington
Hills, IL (US); **Francisco Javier Soria**,
West Chicago, IL (US); **Jeanne M.**
Skaggs, Arlington Heights, IL (US); **Roy**
Speer, Barrington Hills, IL (US);
Milorad Radenovic, Chicago, IL (US)

(73) Assignee: **CLEAR LAM PACKAGING, INC.**,
Elk Grove Village, IL (US)

(**) Term: **14 Years**

(21) Appl. No.: **29/462,099**

(22) Filed: **Jul. 30, 2013**

(51) **LOC (10) Cl.** 09-03

(52) **U.S. Cl.**
